UNITED STATES PATENT OFFICE.

GEORGE B. NASON, OF TOLEDO, OHIO, ASSIGNOR TO CHAMPION SPARK PLUG COMPANY,
OF TOLEDO, OHIO, A CORPORATION OF DELAWARE.

DISPLAY-CABINET.

1,313,498.

Specification of Letters Patent. Patented Aug. 19, 1919.

Application filed April 24, 1919. Serial No. 292,328.

To all whom it may concern:

Be it known that I, GEORGE B. NASON, a citizen of the United States, and a resident of Toledo, in the county of Lucas and State 5 of Ohio, have invented a certain new and useful Display-Cabinet; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 This invention relates to cabinets and particularly to those of the display type, and has for its object the provision of a cabinet of this character which is simple and economical in its construction and which 20 is provided with improved means for securing the front glass therein in a manner to permit an easy removal thereof.

The invention is fully described in the following specification, and while, in its 25 broader aspect, it is capable of embodiment in numerous forms, a preferred embodiment thereof is illustrated in the accompanying drawings, in which;—

Figure 1 is a front perspective view of a 30 cabinet embodying the invention. Fig. 2 is an enlarged fragmentary rear elevation of an upper corner portion thereof. Fig. 3 is an enlarged fragmentary top view of a corner portion with the top plate withdrawn 35 from the glass locking position of the cabinet. Fig. 4 is an enlarged fragmentary vertical section thereof, and Fig. 5 is an enlarged fragmentary horizontal section thereof.

40 Referring to the drawings, 1, 2 and 3 designate the top, sides and bottom of a body frame of a cabinet embodying the invention, which frame is of rectangular form and open at front and back, and is preferably made of wood or other light material. The top and bottom at their ends are preferably, but not necessarily, extended slightly beyond the outer sides of the frame sides, and the bottom is extended at its front edge 45 slightly beyond the front edge plane of the sides.

A back plate 4 closes the rear or back side of the frame, being nailed, screwed or otherwise suitably secured at its edge portions to the rear edge thereof, and this

plate is provided with a plurality of forwardly struck tongues 5 for carrying the articles to be displayed. The tongues, in the present instance, are perforated to facilitate an attaching of the articles thereto which 60 are illustrated as spark plugs.

A casing sheet 6, preferably of sheet metal, entirely covers the back plate 4 at its rear side and extends at its side portions forward around the frame sides, as shown at 65 7, with the forward edges thereof turned inward in forwardly spaced relation to the front edges of the frame sides to form flanges 8. These flanges coöperate with the front edges of the frame sides to form inwardly opening vertical guide grooves 9 for 70 slidably retaining the side edges of the glass 10 closing the front side of the cabinet. This glass rests at its lower edge upon the forwardly extended edge portion of the 75 frame bottom 3 and is preferably of sufficient length for its upper end to lap the front edge of the frame top 1 when the glass is in closed position. A channel strip 11 is fitted around the end and front edges 80 of the bottom 3 in embracing coaction therewith and this strip has an upstanding flange 12 at its inner top edge in advance of the frame opening and in the plane of the flanges 8 to adapt it to lap the lower edge 85 of the glass 10 when in closed position.

A channel strip 13 embraces the extended ends of the frame top 1 and extends across the front edge of the top in forwardly spaced relation thereto to give the top an overhanging front edge effect and at the same time to leave the top edge of the glass 10 90 uncovered to permit its upward withdrawal from the frame.

The top plate 14 of sheet metal, in the 95 present instance, is mounted over the frame top 1 with its end edges engaged under the top edge flanges of the end portions of the channel strip 13 for sliding movements transverse to the top and with its forward 100 edge projected over the glass 10 to close the opening in which it slides and extended into the channel of the front portion of said strip. The rear edge of the plate 10 is provided with a downwardly turned flange 15, 105 which is adapted to closely lap the top edge of the back casing sheet 6 when the top plate is in closed position. The top plate 14 is retained in closed position by the screws 16, which project through the flange 110

15 and upper edges of the back sheet 6 and plate 4 and thread into the rear edge of the frame top 1. If the cabinet is provided with hangers 17 to adapt it to be hung on a 5 wall or other suitable support, such hangers are pivoted at their lower ends to the back sheet 6, as at 18, to adapt them to be swung into or out of obstructing relation to the rear edge of the top plate 14. These 10 hangers may be retained in upright position by inserting the top plate retaining screw 16 through registering apertures 19 in the hangers.

It is evident that I have provided a simple 15 and efficient construction of cabinet for display purposes, the glass 10 of which is secured therein by the top plate 14, and that unless a person understood the purpose of said top plate, it probably would not occur 20 to him that it was employed to secure the glass 10 in position in the cabinet. Inasmuch as the plate 14 cannot be removed without taking the cabinet down from the wall or other object by which supported and 25 removing the screws 16 and turning down the hangers 17, this manner of securing the glass 10 in position tends to prevent an unauthorized opening of the cabinet to remove articles displayed.

30 I wish it understood that my invention is not limited to any specific construction, arrangement or form of the parts as it is capable of numerous modifications and changes without departing from the spirit of the 35 claims.

Having thus described my invention, what I claim as new and desire to secure by Letters Patent, is:

1. A cabinet having a front opening and a 40 top opening and provided with slide-ways at the sides of the front opening, means forming a border member at the sides and front of the top opening, the front portion of 45 which member is in advance of said slide-ways, a closure member for said front opening slidable in said slide-ways through the top opening, and a top plate mounted to

slide in said border member forwardly and rearwardly of the cabinet and when in closed position to stand over said slide-ways to 50 prevent a removal of the closure member therefrom and having its forward edge entering the front portion of said border member.

2. A cabinet having a front opening and 55 a top opening at the upper edge of the front opening and provided with slide-ways at the sides of said openings, a glass plate slidably mounted in one of said ways and closing said front opening and removable therefrom through the top opening, a top plate mounted for sliding movements over the cabinet top and adapted to close said top opening over the glass plate, and cabinet hangers movably secured to the back of the 60 cabinet and when in usable position coacting with said top plate to retain it in closed position.

3. In a display cabinet, a body frame having a closed back and an open front, the 70 frame bottom extending forward beyond the front edge of the frame top, means embracing the frame sides and forming flanges at the front edges of said sides to coöperate therewith to form slide-ways, a glass plate 75 for closing the frame front, said plate being slidably mounted at its side edges in said slide-ways with its bottom resting on the front edge of the frame bottom, a transversely angled strip extending around the 80 end and front edges of the frame top in spaced relation to the front edge thereof to coöperate with the top to form an opening in register with the glass plate through which it may be removed, a plate slidably 85 over said top in position to close said top opening and with its end and front edges slidably lapped by said strip, and removable means securing said top plate in closed position.

In testimony whereof I have hereunto signed my name to this specification.

GEORGE B. NASON.
